UNITED STATES PATENT OFFICE

103,249

DESIGN FOR A CHAIR

Frank T. Parrish, Gardner, Mass., assignor to
Heywood-Wakefield Company, Boston, Mass., a
corporation of Massachusetts

Application January 7, 1937, Serial No. 66,936

Term of patent 7 years

To all whom it may concern:

Be it known that I, Frank T. Parrish, a citizen of the United States, residing at Gardner, in the county of Worcester and Commonwealth of Massachusetts, have invented a new, original, and ornamental Design for a Chair, of which the following is a specification, reference being had to the accompanying drawing, forming part thereof, in which

Fig. 1 is a perspective view of a chair showing my design.

Fig. 2 is a larger scale sectional view on the lines 2—2 of Fig. 1.

As shown in the drawing, the front legs of

the chair are of quarter-round section, and their outwardly faced convex surfaces are on substantially the same radius as and, therefore, flush with the rounded lower front corners of the chair seat; the latter's rounded-over edges merge at said corners with said convex front leg surfaces, and along the front and sides with the flat boxing surfaces which in turn are flush with said convex front leg surfaces in their zones of junction with said front legs.

I claim:

The ornamental design for a chair, as shown and described.

FRANK T. PARRISH.
